TABLE

Bert J. Klein and Andre Bus, Altavista, and John B. Thorn, Lynchburg, Va., assignors to The Lane Company, Inc., Altavista, Va., a corporation of Virginia

Filed Apr. 19, 1965, Ser. No. 84,870

Term of patent 14 years

(Cl. D33—14)

Fig. 1.

Fig. 3.

Fig. 2.

The side and end not shown of each table is like the side and end shown.

We claim:

The ornamental design for a table, as shown and described.
